DESIGN FOR A SCREEN FOR A DOLL'S HOUSE

Natalie Kropatkin, Bronx, N. Y.

Application April 10, 1945, Serial No. 118,937

Term of patent 7 years

(Cl. D34—15)

To all whom it may concern:

Be it known that I, Natalie Kropatkin, a citizen of the United States of America, residing in Bronx, county of Bronx, and State of New York, have invented a new, original, and ornamental Design for a Screen for a Doll's House, of which the following is a specification, reference being had to the accompanying drawing, forming part thereof.

The figure on the drawing is a perspective view of a screen for a doll's house showing my new design.

I claim:

The ornamental design for a screen for a doll's house, substantially as shown.

NATALIE KROPATKIN.
